FOLDING ARTICLE OF FURNITURE

John Kovats, Fairfield, Conn., assignor to The Leg-O-Matic Company, Bridgeport, Conn., a corporation of Connecticut

Application December 19, 1933, Serial No. 703,050

4 Claims. (Cl. 311—82)

This invention relates to folding tables, and especially card or game tables.

It is an object of the present invention to provide an improved mechanism for supporting folding legs in both the extended and folded positions, and improved operating connections for effecting conjoint positioning of all the legs on the table through the manual operation of any one of the legs and for maintaining the legs in either the folded or the extended position.

It is a further object of the present invention to provide means for individually maintaining and locking each of the several legs of the table in extended or working position, and yet release all of the legs when any one of them is released to allow all of the legs to be folded simultaneously.

A feature of the present invention is the provision of means for automatically completing the movements of the legs as they approach extended or folded position close to the table top and to yieldingly hold the legs in folded position so that in handling they will not casually swing away from the table top.

Other features and advantages will hereinafter appear.

In the accompanying drawing—

Figure 1 is a bottom plan view of a table made in accordance with this invention, with the legs in extended position.

Fig. 2 is a fragmentary view of one corner of a table showing the leg folded against the table top.

Fig. 3 is a view similar to Fig. 2, showing the leg extended to operative position.

Fig. 4 is a fragmentary bottom plan view of the parts shown in Fig. 3.

As shown in the accompanying drawing, the present invention is applied to a card table of the type wherein the legs 10 fold perimetrically within the marginal frame 11 of the table top 12, the underside of which is shown in Fig. 1. Each leg is secured to a metal plate 13 having a barrel 14 much wider than the width of the leg and receiving a pin 15 carried by a bracket 16. The bracket 16 fits in the corner formed by the adjoining sides 11a of the marginal frame 11 and being secured to these parts serves as a brace as well as a hinge part and mounting plate for the actuating mechanism.

The legs 10 are moved from folded position shown in Fig. 2 to extended operative position shown in Fig. 3, and vice versa, by an actuating mechanism including a pair of toggle links 17 and 18 hinged together at 19 for each leg. Each link 17 is connected to one of the legs 10 by a pivot pin 20, and each link 18 is connected to the table top by a

pivot pin 21 which is carried by an extension 22 of the bracket 16. The toggles 17 and 18 are so positioned and are of such length that when the leg is vertical the common pivot point 19 of each toggle will move down past a line drawn through the centers of pivots 20 and 21 and thereby lock the legs in extended or vertical positions, each leg being locked individually of its own toggle.

Each toggle link 18 is connected to a spring 23 having its other end bearing against the extension 22 of the bracket and having at this point a loop receiving a screw 24 for holding the spring against slipping out from engagement with the plate. The spring is so positioned that when the toggle approaches fully extended position the spring will act to throw the toggle to its locking position shown in Fig. 3.

It is also so positioned that when the toggle is collapsed and the leg is folded up against the table top as shown in Fig. 2, the spring will urge the toggle link 18 upwardly and hold the leg in folded position against accidentally falling down. The spring may be strong enough so that, when its end which engages the toggle link 18 crosses a line between the centers of the pivot pin 21 and the screw 24, it will complete the motion of the toggle and thus complete the motion of the leg to either extended or folded position, the movement of the toggle being limited by a stop pin 25 secured in the extension 22 and riding in a slot 26 in an arm 27 integral with the link 18, the ends of the slots engaging the pin to limit the movements of the link 18, toggle, and leg.

When it is desired to swing the legs upwardly to their folded position, the toggle lock may be broken by pressing upwardly against the link 18. However, when the spring 23 is made strong enough to complete the movements of the leg in both directions, considerable force must be applied to the toggle because of the short leverage. To facilitate the breaking of the toggle, the present invention provides an actuating lever 28 pivoted on the pin 21 and having a long handle 29. The actuating lever 28 has a portion 30 engaging a shoulder 31 on the link 18. Hence, when the lever is pulled from the full line to the dot-and-dash line position shown in Fig. 3, the links 17 and 18 are swung to the dotted line positions where the toggle lock is broken and further collapsing movement of the toggle may be effected by power applied to the leg or to the link 18.

The table thus far described may be operated by moving each leg separately from its folded

to its operative or extended position, and a very useful and satisfactory article results.

However, in order to facilitate the opening and closing of the table, a common actuating device is provided for all the legs.

This comprises a bell crank lever 32 pivoted at 33 on a plate 34 in each corner of the table. The plate 34 may be made integral with the bracket 16, or it may be made of a separate piece 10 inserted between the bracket 16 and the marginal frame 11. Connecting these bell crank levers are four links 35 so that when one link moves all of the links move. Each link is provided with a coupling member 36 slotted to engage a pin 37 carried by the arm 27 of the toggle link 18, and it is by means of the pin and slot connection between the coupling 36 and the pin 37 that all of the legs are moved simultaneously when any one of the legs is moved. By coupling 15 the connecting mechanism, including the bell cranks 32 and links 35 to the arm 18 of the toggle, the movement of any one leg incidental to the breaking of the toggles 17 and 18 of that leg will also break the toggle locks of the other legs, and the continued movement of the leg being manipulated will cause the other legs to move simultaneously and to the same extent.

Likewise, when the legs are to be moved from the folded position shown in Fig. 2 to the extended position shown in Fig. 3, the manual moving of any one leg will cause all of the legs to move.

In order to avoid lateral movement of the toggle links relative to each other, the toggle link 17 35 is provided with an extension 17a lying parallel with and against the link 18 when the toggle links are in their extended positions shown in Fig. 3.

Variations and modifications may be made 40 within the scope of this invention and portions of the improvements may be used without others.

Having thus described the invention, what is claimed as new and for which it is desired to obtain Letters Patent, is:—

45 1. In a folding table, the combination of a table top; a plurality of legs; means for hinging the legs on the table top for movement to and from extended and folded positions; a pair of toggle links between each leg and the table top, one of 50 said links being pivoted on each leg and the other of said links being pivoted on the table top; means interconnecting the latter links for simultaneous movement whereby all of the links will

operate together and all of the legs will be folded and extended simultaneously; and a plurality of springs, one spring acting directly on each pair of toggle links to start and complete the movements thereof.

5 2. In a folding table, the combination of a table top; a plurality of legs; means for hinging the legs on the table top for movement to and from extended and folded positions; a pair of toggle links between each leg and the table top 10 for locking the leg in extended position; means interconnecting the toggle connections for the several legs for simultaneous movement; and a manually operable lever having a one-way driving connection with one of the toggle links for 15 breaking the toggle connections to unlock the legs to permit them to be folded.

3. In a folding table, the combination of a table top; a plurality of legs; means for hinging the legs on the table top for movement to and 20 from extended and folded positions; toggle links connecting each leg to the table top; means yielding directly and independently acting on each pair of toggle links for causing the latter to automatically complete the movement of the leg 25 into either folded or extended positions as the legs approach either the one or the other of said positions respectively; and means acting on said toggle links for interconnecting the legs for simultaneous movement of all by one.

30 4. In a folding table, the combination of a table top; a plurality of legs; means for hinging the legs on the table top for movement to and from extended and folded positions; toggle links connecting each leg to the table top; means yielding directly and independently acting on each 35 pair of toggle links for causing the latter to automatically complete the movement of the leg into either folded or extended position as the legs approach either the one or the other of said positions respectively, said means acting to cause the legs to be locked in extended position and to be held in folded position against casual displacement; means for interconnecting the legs for 40 simultaneous movement of all by one, said interconnecting means causing all of the legs to be unlocked when one of them is manually unlocked; and a manually operable lever for breaking the locking action of said toggle links to unlock the legs to permit them to be folded.

45 JOHN KOVATS.
